STERNPOST CONSTRUCTION

Everett Chapman, Coatesville, Pa.

Application August 27, 1934, Serial No. 741,650
Renewed January 24, 1939

11 Claims. (Cl. 114—169)

My invention relates to ship construction and the object of my invention is to provide an improved form of sternpost or rudder support, which sternpost has been designed to resist the usual loads which tend to bend and twist the same. Depending upon the size of the ship, these sternposts are of very great weight. For instance, in a ship of ten thousand (10,000) tons displacement, the sternpost may have a weight in excess of fifteen tons.

By reason of the duty imposed upon sternpost structures, it is necessary that they be highly resistant to load stresses tending to bend and twist the same. The predominant load on a sternpost has a bending and twisting tendency, and the principal object of my invention is to provide a structure in which the resistance to bend and twist is so greatly increased as to practically avoid failure due to such load factors.

The normal loading on a rudder post is the force resulting from rudder action when the latter is placed at an angle with respect to the direction the ship is moving. As is well known, the rudder under these conditions will have a certain centre of pressure at which the load which changes the direction of the ship may be considered to be concentrated. This centre of pressure, in general, may be away from the hull of the ship by as much as ten feet (10') in a vertical direction and as much as ten feet (10') in a horizontal direction from the nearest available point of attachment of the supporting structure—the rudder or sternpost—to the ship's hull. This force then tends to bend the stern or rudderpost at the line of the hull in a direction perpendicular to the longitudinal axis of the ship and also tends to twist off the rudderpost.

In view of the type of load which predominates in this type of structure, I have endeavored to introduced a metal section of a character calculated and best adapted to resist such a type of load. To this end, my invention comprises a wholly tubular rudder or sternpost whose cross-sectional contour of the main strength or main load-resisting member may be a polygon of not less than four sides, and preferably is of cylindrical or circular contour.

The ideal section for resisting a torsional load is, of course, a tube which in addition is an effective member for resisting bending moments when it acts as a beam cantilevered out from the hull. As an alternative, in those cases where the bending load may predominate over the torsional load, a square tube may be the choice of the designer. A square tube is more effective

than a round tube for resisting bending and is only slightly less effective from a torsion-resisting standpoint. In the use of a square tube, round fillets should be employed at all corners internally of the same.

Between these two cross-sections lie a variety of polygonal sectional contours, any one of which may be equally adaptable and capable of performing the functions assigned to the round or square section rudder or sternpost. The usual stream-lined, pear-shape, sternpost is deficient in torsional strength and ineffective from a bending standpoint in the plane in which these rudder or sternposts deflect. The tubular post of my construction can, of course, be stream-lined to reduce the parasitic drag of the ship by means of properly shaped relatively light gauge plates disposed forwardly of the same.

Various means may be employed for producing a tubular rudderpost within the scope of my invention. For instance, it may be cast as a single section which will include the necessary upper and lower gudgeons or bearing supports for the rudder shaft. In order that the tubular portion of such rudderpost may be developed, the casting may be cored and similar means may be employed to provide the openings in the gudgeons or bearing supports, such openings being subsequently finished as may be necessary or desirable; the openings of the gudgeons or supports receiving the usual bronze bushings for the rudder shaft. In lieu of this arrangement, the sternpost may be made of plate, shaped to the desired cylindrical or polygonal form. If polygonal, it may be made up of a plurality of plate sections or pre-formed shapes welded together, and if a sectional form is employed, this will be the desirable manner of producing the same. Polygonal shapes might be produced by bending one or more sections to give the desired wall contour. A cylindrical structure may be developed from a single plate bent into the desired contour and having its meeting edges welded together.

In providing the desired gudgeons for a tubular rudder base or sternpost, the upper gudgeon may be a separate tubular element welded to the main body of the tubular post, while the lower gudgeon may be a separate element welded in place, or it may be a cast section to which the tubular stern or rudderpost is attached as by welding and then bored through for the sake of lightness in the axis of the tubular stern or rudderpost. If desired, the lower opening of this bottom section, or the bottom of a completely tubular post may be closed by a plate which may be welded in place.

These and other features of my invention are more fully described hereinafter, reference being had to the accompanying drawings, more or less diagrammatic in character, in which:

- 5 Figure 1 is a view in elevation of the stern of a ship showing the position of my improved stern or rudderpost structure with respect to the same.
- Fig. 2 is a plan view of my improved stern or rudderpost structure on a larger scale.
- 10 Fig. 3 is a sectional elevation on the line III—III, Fig. 2.
- Fig. 4 is a sectional view on the line IV—IV, Fig. 3, looking in the direction of the arrow a .
- 15 Fig. 5 is a plan view of a part of the structure, in section, on the line V—V, Fig. 1, and
- Fig. 6 is a sectional view illustrating a modified form of the main strength or load-resisting member of my improved structure.
- The improved stern or rudderpost construction
- 20 forming the subject of my invention includes essentially a main strength or load-supporting element, preferably of tubular cross-sectional contour, supported by and tied in with the plates of the hull of the ship at the stern of the same.
- 25 This element is indicated at 10, Figs. 1, 2, and 3, where it is shown as a section of a cylinder of proper dimensions—length and diameter. This member is associated with and carries a gudgeon receiving the rudder shaft. While, in some instances, a single gudgeon may be employed, I prefer to employ two gudgeons, an upper gudgeon indicated at 11, and a lower gudgeon indicated at 12. These gudgeons may carry the usual bronze bushings in which the rudder shaft 13, carrying
- 30 a rudder 14, is mounted, and such rudder may be of the usual stream-lined contour, fore and aft. The upper gudgeon may be annularly recessed, as indicated at 11^a to support the bronze bearing bushing.
- 35 40 The upper gudgeon 11 is maintained in the desired position with respect to the main strength or load-supporting member by means of a cover plate 15, welded thereto in any approved manner, the welds being indicated at x , and in addition this gudgeon may be welded to the member 10 at x' . The cover plate is apertured at 15^a for the passage of the rudder shaft and at 15^b to gain access to the interior of the member 10 to permit welding. In Figs. 3 and 4, I have shown the lower gudgeon as a separate member and, in the present instance, it is shown as being supported
- 45 by plates 16 and 17 of the shape more particularly shown in Fig. 5, said plates having strap portions 16^a and 17^a surrounding said gudgeon and welded thereto, and portions welded to the member 10. The lower plate 17 may extend beneath the tubular member 10 in the manner indicated in Fig. 3, such arrangement closing the bottom of the latter and preventing entrance of
- 50 55 the sea. This lower gudgeon may be in the form of a casting or forging, secured to a member such as the member 10 by welding, and then bored through in the axis of said member for the sake of lightness, such member, of course, providing for the passage of the rudder shaft, and having the portion beneath the supporting member closed by suitable means. In addition, vertically disposed plates 18 and 19 may be secured to the upper gudgeon and the member 10 as by welding, being disposed over the plate 16 to which
- 60 65 70 they may also be welded.
- The stern or rudderpost structure comprising the member 10 and the upper and lower gudgeons 11 and 12 is tied in with the hull of the ship by a plate frame or shell which may consist of the

angularly disposed side plates 20, fore and aft transversely arranged plates 21 and 22, and the underlying plates 23 and 24 which follow the line or plane of the hull and in addition to being welded together are interconnected with the plates of the latter, longitudinally and transversely, as indicated by the rivet joints 25, Figs. 3 and 4. Bracing plates 26 may also be disposed forwardly of the member 10. These several plates of the frame or shell are reinforced or supported in proper relative position with respect to the rudder or sternpost and the upper gudgeon 11 by means of a series of tie plates 27, usually vertically arranged, and radially disposed with respect to the member 10 and the gudgeon 11, as clearly indicated in Fig. 2, such tie plates being welded to the walls of the shell and the other contacting parts of the structure, as indicated at x^2 , Fig. 2.

The member 10 is preferably provided with internally disposed tie plates 30 and 31, as clearly shown in Fig. 3, the upper plate 30 following the line of the plates 23 which form part of the bottom of such shell and additionally that much of the hull of the ship. The member 10 may be stream-lined forwardly by the employment of light gauge plates 32, welded thereto and to the plates 23, as indicated at x^3 , Figs. 3 and 5.

The member 10 illustrated in the drawings, tubular in form, may be a section of tubing of the desired weight and character, or it may be made of a plate of proper weight rolled or bent into shape and having its meeting edges welded together. It may be in the form of a casting or forging, hollow or solid, and, if solid, subsequently bored to provide the desired tubular contour, or it may be in the form of a tube having a polygonal cross-sectional contour and range from a four-sided polygon to one of many sides—just short of or extending to a completely cylindrical form. If of polygonal shape—square, for instance—it may be built of a pair of bent channel sections 10^a, as indicated in Fig. 6, welded together at the lines x^4 . If a section of this type is employed, the corner bends will have internally a radius not less than the thickness of the metal making up the wall of such member. If the polygonally shaped tube is developed from four or more plates, for instance, the inner corners will have rounded fillets welded to the walls of such built-up member.

I have employed the words "tube" and "tubular" in the foregoing specification to indicate the hollow main load-supporting or strength member of my improved stern or rudder post structure. By "tube" and "tubular" is meant a hollow body having a cross-sectional contour which may range through polygonal contours (not less than four sides) to a cylindrical structure, and it is to be so understood in the claims.

Various modifications may be made in the foregoing embodiment of my invention without departing from the spirit and scope thereof as set forth in the appended claims.

I claim:

1. The combination with the hull of a ship, of a rudder mounting comprising a hollow load-resisting member connected to said hull in a vertical position and terminating a short distance below the same, a rudder, a shaft carrying the same, upper and lower bearing gudgeons for said shaft connected to said main load-resisting member, stay members for said load-resisting member framed into the hull fore and aft, diagonally and laterally with respect to the same, 75

5 a plate framed into the hull structure and forming a connection between the upper gudgeon and the load-resisting member; said upper gudgeon lying substantially within the hull, and connections between the lower bearing gudgeon and the load-resisting member.

2. The combination with the hull of a ship, of a rudder mounting comprising a hollow load-resisting member connected to said hull in a vertical position and terminating a short distance below the same, a rudder, a shaft carrying the same, upper and lower bearing gudgeons for said shaft connected to said hollow load-resisting member, stay plates vertically disposed connected to said hollow load-resisting member fore and aft, diagonally and laterally with respect to the same and framed into the hull of the ship, a continuous plate framed into the hull structure and forming a connection between the upper gudgeon, 10 the load-resisting member and said stay plates, and connections between the lower bearing gudgeon and said load-resisting member; said connections including a plate which underlies the hollow load-resisting member.

25 3. The combination with the hull of a ship, of a rudder, a shaft therefor, a supporting gudgeon for said shaft, a hollow load-resisting member connected to said hull and terminating a short distance below the same; said hollow member carrying said gudgeon and having wall sections distributed at substantially the same radius around a central axis, and vertically disposed stay plates framed into said hull and disposed fore and aft, diagonally and laterally with respect to 30 said hollow supporting member and permanently connected thereto.

4. The combination with the hull of a ship, of a rudder, a shaft therefor, a supporting gudgeon for said shaft, a hollow load-resisting member connected to said hull and terminating a short distance below the same; said hollow member carrying said gudgeon and having a cross sectional contour in the form of a polygon of at least four sides, and vertically disposed stay plates 40 framed into said hull and disposed fore and aft, diagonally and laterally with respect to said hollow supporting member and permanently connected thereto.

5. The combination, with the overhanging 50 stern structure of a ship's hull, of a rudderpost structure built into said overhanging stern structure and comprising a fixed tubular member depending from and terminating a short distance below said overhanging stern structure, and rudder shaft supporting means carried by said tubular member and disposed in parallel relationship therewith.

6. The combination, with the overhanging 55 stern structure of a ship's hull, of a rudderpost structure built into said overhanging stern structure and depending from and terminating a short distance below the same; said rudderpost structure comprising a main strength or load-resisting member of tubular form, and tubular rudder-shaft-supporting means carried by said load-re-

sisting member and disposed in parallel relationship therewith.

7. The combination, with the overhanging stern structure of a ship's hull, of a fixed rudderpost structure including a member of tubular construction built into said overhanging stern structure and depending from and terminating a short distance below the same; said tubular member having portions of its walls symmetrical disposed with respect to a central axis, and 10 rudder-shaft-supporting means carried by said tubular member and disposed in parallel relationship therewith.

8. The combination with the hull of a ship having an overhanging stern portion, a rudder 15 and a shaft therefor, of a rudder mounting framed into said hull; said rudder mounting comprising a fixed rudderpost and main strength or load-resisting member of tubular formation depending from and terminating a short distance 20 below the overhanging portion of the hull, and tubular means carried by said load-resisting member and disposed in parallel and fixed relationship therewith for supporting the rudder shaft.

25 9. The combination with the hull of a ship having an overhanging stern portion, a rudder and a shaft therefor, of a rudder mounting framed into said hull and comprising a fixed rudderpost or main strength member of tubular 30 formation depending from and terminating a short distance below the overhanging portion of the hull, and laterally disposed bearing gudgeons carried by said depending rudderpost and disposed in parallel relationship therewith for sup- 35 porting the rudder shaft.

10. In a rudder mounting for ships, the combination with the hull, a rudder and a shaft carrying the same, of a hollow main load-resisting member of tubular formation perpendicularly arranged with respect to the horizontal cross axis of the hull and depending therefrom, a bearing gudgeon for said shaft carried by said tubular main load-resisting member in parallel relationship therewith, and a frame supporting said rudder mounting and including an upper plate connected to said tubular main load-resisting member and disposed within the hull.

40 11. In a rudder mounting for ships having an overhanging stern portion, the combination with the hull, a rudder and a shaft carrying the latter, of a hollow main load-resisting member perpendicularly arranged with respect to the horizontal cross axis of the hull and depending from and terminating a short distance below the overhanging portion of the hull, upper and lower bearing gudgeons for said shaft carried by said main load-resisting member in spaced relation vertically and in parallel relationship therewith, and a frame supporting said rudder mounting and including an upper plate connected to said load-resisting member and the upper bearing gudgeon and disposed within said hull.
